BY *Coronelius Gabriele*
ATTORNEYS.

UNITED STATES PATENT OFFICE.

IGNATZ SIDON, OF ASTORIA, NEW YORK.

BOOK CARRIER.

Application filed March 18, 1927. Serial No. 176,356.

This invention is a book carrier adapted more especially for use by school children, and the purpose of the invention is primarily to provide in a very simple and economical construction a thoroughly sanitary device for the carrying of books.

In many of the larger cities and particularly in the tenement districts, school children are not permitted to employ book straps and brief cases because they are considered unsanitary.

The present invention is a thoroughly sanitary construction which may be sterilized, if desired, and fulfills all the requirements of the school authorities, as well as the functional requirements of a book carrier. Book carriers made of metal have heretofore been suggested, but, in every instance, they are relatively expensive and embody at least several parts, among which are generally included tubular elements which obviously are unsanitary as proper cleaning of the interior of tubes in a construction of this character is practically impossible.

The present invention, in contradistinction, may be made of a single piece of wire bent to form a bail. At the base of the bail are formed integral clamping jaws which cooperate with the opposite faces of the bail to clamp books between the respective jaws and the bail.

In one of its practical forms, the holder is made of two pieces of wire twisted together to form the bail and to secure the two lengths of wire permanently to one another by a simple twisting operation. At the base of the bail, each piece of wire is carried laterally to form in the central portion of the wire length a clamping jaw including coils which impart considerable inherent resiliency to the jaws. The free ends of the wires terminate at the top of the bail and are introduced into the opposite ends of a wooden or metal handle, although, in practice, they may be soldered, welded together, or twisted together at this point.

The construction is unusually simple mechanically, may be economically manufactured and is thoroughly sanitary. Furthermore, it is highly efficient in the carrying out of its intended purposes and has a relatively large capacity for the carrying of books.

An important feature of the invention consists in the formation of the bail by the

twisting of the wire or wires together. This arrangement produces a very rigid construction in a very economical manner and entirely obviates the necessity of employing tubular or other extraneous parts in the formation of the bail. The bail is thus formed integral with and of the same wire as is employed in the formation of the clamping jaws and results in a light, strong, durable and efficient construction.

Features of the invention, other than those adverted to, will be apparent from the hereinafter detailed description and claims, when read in conjunction with the accompanying drawings.

The accompanying drawing illustrates one practical embodiment of the invention, but the construction therein shown is to be understood as illustrative, only, and not as defining the limits of the invention.

The drawing shows the holder of the present invention in perspective with one book supported therein.

Referring to the drawing, 1 designates a bail, 2 a handle therefor and 3 and 3^a cooperating clamping jaws in which are formed coil spring elements 4 and 4^a.

In the preferred manner of making the device, two lengths of wire are employed. Each piece of wire is bent to form midway of its length a jaw shaped as shown at 3 and 3^a. At the base of the jaws, the wires are bent to form the coils 4 and 4^a and are then brought together at the points 5, and the remainder of the length of the wire is twisted to form the opposite vertical sides 6 of the bail. The upper ends of these opposite sides are bent toward one another as shown at 7 and forced into the opposite ends of a handle 2.

This is the preferred form of construction, although, in practice, the handle 2 may be dispensed with, and the portions 7 of the wire may be made longer, so as to overlap one another and may be twisted or soldered together.

It is also within the purview of this invention to form the whole construction from a single piece of wire and if the free ends of the wire meet either within the handle 2 or be coiled around an uninterrupted portion of the wire extending across the top of the bail. I have not considered it necessary to show these alternative forms of the in-

vention, as they will be apparent to anyone skilled in the art.

The jaws 3 and 3^a are preferably bent as shown in the drawings, so that when they are sprung apart to their maximum extent, the portions 8 and 8^a of the respective jaws will be substantially vertical, while the portions 9 and 9^a of said jaws will be substantially horizontal. The upper ends of the 10 jaws are deflected outwardly as shown at 10 and 10^a to provide with the bail a re-entrant mouth in order to facilitate the introduction of books between these parts.

The structure is unusually simple, may be 15 manufactured at a minimum cost and embodies at most two pieces of wire and an attached handle, while in simplest form, it may be made of a one piece integral construction.

20 I place particular stress upon the twisting of the wires together to form the sides 6 of the bail as this arrangement renders the bail very rigid as is essential for the proper functioning of the construction particularly 25 when books are carried in only one side of the bail as shown in the drawing.

The drawing illustrates the invention in its preferred practical form, but the invention is to be understood as fully commensurate 30 with the appended claims.

Having thus fully described the invention,

what I claim as new and desire to secure by Letters Patent is:

1. In a book holder, a pair of wire loops 35 constituting opposed clamping jaws, the wires from which said loops are formed being provided at the bases of the loops with spring coils and the wires of the two loops being extended from said coils toward one another and twisted together to form 40 standing members constituting the side members of a bail, the upper portions of said side members being bent toward one another and secured together to form a handle to the bail.

2. In a book holder, a pair of wire loops 45 constituting opposed clamping jaws, the wires from which said loops are formed being provided at the bases of the loops with spring coils and the wires of the two loops being extended from said coils toward one another and twisted together to form 50 standing members constituting the side members of a bail, the upper portions of said side members being bent toward one another, 55 a handle member provided in its opposite ends with holes into which the bent portions of the bail extend to anchor the side portions of the bail to the handle.

In testimony whereof I have signed the 60 foregoing specification.

IGNATZ SIDON.
